UNITED STATES PATENT OFFICE.

MAX N. KEELER, OF URBANA, ILLINOIS.

WINDOW STRUCTURE.

1,221,186.

Specification of Letters Patent.

Patented Apr. 3, 1917.

Application filed April 14, 1915. Serial No. 21,272.

To all whom it may concern:

Be it known that I, MAX N. KEELER, a citizen of the United States, residing at Urbana, in the county of Champaign and 5 State of Illinois, have invented certain new and useful Improvements in Window Structures, of which the following is a specification, reference being had therein to the accompanying drawing.

10 This invention relates broadly to window structures and more especially to window swinging and locking devices.

The object of the invention is to provide simple and effective means that are readily 15 and conveniently manipulated for swinging and locking a window without disturbing a screen which is also therein disposed.

Another object is to provide window swinging and fastening instrumentalities, of 20 the type specified, which do not present an unsightly appearance.

Still another object within the contemplation of my invention is to juxtapose the swinging instrumentality to the locking instrumentality so that they may be operated 25 in conjunction, one with the other and whereby, when the window has been unlocked by the one instrumentality, it may be swung outwardly by the other.

30 This invention in general seeks to provide a window-structure which is particularly adapted for use in window-casements wherein a screen is also mounted; and which structure from an operative standpoint will in 35 practical use possess a high degree of efficiency and durability and which structurally considered will be of great simplicity.

There are other objects and advantages 40 present in the invention, and these will be obvious from the accompanying drawings and the following description.

The invention resides broadly in the features of construction and in the novel correlative aggroupment thereof, all as exemplified in the construction hereinafter set forth, and the scope of application of which will be indicated in the claim hereto appended.

In order that the invention may be readily 50 comprehended, drawings illustrating a preferred embodiment and utilization of the same are hereto appended as a part of this disclosure, it being manifest that other embodiments and utilizations (employing the 55 underlying principles of my invention) fall

within the spirit thereof and within the objects contemplated thereby.

In these drawings:

Figure 1 is a view in front elevation of a window-casement with my invention applied thereto;

Fig. 2 is a view in vertical section of the same;

Fig. 3 is a view in horizontal transverse section on the line 3—3, Fig. 2; and

Fig. 4 is a fragmentary view in section of one portion of the structure.

In these drawings, the reference-numeral 1 designates the front or outer portion of a window-casement; 2 the rear or inner portion thereof; 3 the stool-portion, and 4 the top-piece.

Hinged or otherwise attached to the inner portion 2 of the casement is a screen 5 of any suitable form and construction.

Hinged as at 6, or otherwise attached, to the outer portion 1 of the casement is a window 7 of usual construction.

The stool-portion 3 is provided with a slot 8 in which a window-actuating device 80 has movement. This device comprises a swinging arm 9 pivotally attached (as at 10) to the lower portion of the window, and a rack-arm 11 pivotally connected to the inner end of the arm 9. The arm 9 is of a 85 length equal to the distance, approximately, between the pivot 10 and the plane of the front face 12 of the stool-portion. The arm 11 is of about the same length. Hence, when the window is closed, as shown in 90 Figs. 1 and 3, for instance, the arm 11 will lie parallel to the front face of the stool-portion while the arm 9 will occupy a position substantially at right-angles thereto, and, thus, beneath the overhanging-ledge of the 95 stool.

Secured to the stool-portion and in alignment with the slot 8 is a rack-engaging plate 13 with which a series of teeth 14 on the rack-arm 11 are engageable. Thereby, the 100 window-actuating device may be held against movement and, thus, the window is rigidly held against closing. When the rack-arm 11 is in the aforementioned angular position shown in Figs. 1 and 3, the 105 window is securely held against opening.

To supplement this holding action of the window-operating device, I may provide a window-locking device. In this instance, this device is shown as including a vertical 110

spindle 14^a journaled at 15 and 16 in the casement. It carries a series of hooks or angular projections 17 that are adapted to engage a corresponding series of eyes 18 on the window-sash.

Means are provided for rotating the spindle, and these comprise a pinion 19 fast on the lower end of the spindle and meshing with a corresponding pinion 20 on the outer end of 10 a stub-shaft 21 journaled in the casement. This, in turn, carries a crank 22 on its inner end.

Operation: Assuming that the window is closed, as shown in full lines in Fig. 3, and it 15 be desired to open it, the operator turns the crank 22. This rotates the shaft 21 and, through the pinions 19 and 20, the spindle 14^a. In this way, the hooks are withdrawn from the window-eyes. Thus, the window is 20 free to be opened. This opening is accomplished by swinging the rack-arm so that it will occupy the position shown in dotted lines in Fig. 3. The operator then pushes on the rack-arm and this causes the swinging 25 arm to swing the window outwardly on its hinge. The rack-arm may then engage the plate 13, as shown in Fig. 4, and this will lock the window in its opened position.

If, now, it be desired to close the window, 30 the operator disengages the rack-arm from the plate by lifting the former slightly and, then, pulls the actuating device inwardly. When the window has thus been closed, the 35 rack-arm is swung back to its angular position and serves to lock the window. The crank may then be manipulated to effect an engagement of its hooks with the window-eyes so that the window is, thereby, additionally locked.

40 As will be seen, these operations of swinging the window and locking and unlocking it may be accomplished without disturbing the screen 5.

It is within the contemplation of my 45 invention to utilize the disclosed structure for positioning and locking swinging instrumentalities other than windows.

From the foregoing, it will be perceived 50 that I have succeeded in devising a window-operating structure which is well adapted to achieve the objects and ends in view.

It is to be understood that the particular

embodiment herein shown and described is exemplary and that all matter contained in the foregoing description and shown in the 55 accompanying drawings shall be interpreted as illustrative and not in a limiting sense.

What I claim is:

A window structure comprising a casement provided with a triangular recess, disposed with a base thereof forming an enlarged opening on the outer side of the casement, and the apex thereof forming a restricted opening upon the inner surface of the casement; a window hinged in proximity 60 to the enlarged opening formed by said recess; and a window locking and actuating device comprising a swinging arm pivotally connected to said window at a point removed from its hinged connection to the 65 casement; said arm being of a length approximately equal to the width of the casement and normally occupying a position within the recess; a portion of the free end of said arm protruding beyond the inner 70 surface of the casement when the window is in closed position; a rack arm having at one 75 end a handle, and pivotally connected at its opposite end to the swinging arm; said rack arm normally occupying a position outside 80 the restricted opening formed by said recess on the inner side of the casement, and in approximate alinement with said inner side for locking the window in its closed position; and a rack plate secured to the casement at an edge of the restricted opening in 85 the triangular recess, and adapted to be engaged by the rack arm when the latter occupies a position within the triangular recess to hold the window in a plurality of 90 positions; said swinging arm having a longitudinal movement at its free end, in the triangular recess, approximately equal to the widest portion of said recess, said swinging being effected upon its point of connection 95 with the rack arm as a pivot, when the rack arm is actuated to open the window.

In testimony whereof I affix my signature in presence of two witnesses.

MAX N. KEELER.
